UNITED STATES PATENT OFFICE.

ROBERT ALEX RUTLAND, OF ALAPAHHA, GEORGIA.

PORTABLE SHOWER-BATH.

1,147,648.

Specification of Letters Patent.

Patented July 20, 1915.

Application filed December 30, 1914. Serial No. 879,735.

To all whom it may concern:

Be it known that I, ROBERT A. RUTLAND, a citizen of the United States, residing at Alapaha, in the county of Berrien and State 5 of Georgia, have invented certain new and useful Improvements in Portable Shower-Baths; and I do hereby declare the following to be a full, clear, and exact description of the invention, such as will enable others 10 skilled in the art to which it appertains to make and use the same.

This invention comprehends certain new and useful improvements in portable shower baths, and has for its primary object to 15 provide a device of this character which will be of such construction that it may be readily transported from place to place, will be cheap to manufacture and strong and durable as well as highly efficient in use.

20 This invention has for another object to provide a portable shower bath of the above stated character including a body with a door, a tub beneath said body and a flange for directing water to said tub, a tank secured upon said body with a shower member or attachment depending from the same and means for controlling the discharge of the liquid from the tank through the shower member.

30 The invention has for a further object to provide a device of this character which will be of improved and novel form and will include a shower nozzle depending from a tank positioned upon the reduced upper end 35 of the body and having a valve positioned against its outlet above the shower nozzle and a flexible member connected with said valve and extending into the body, whereby the bather may readily control the discharge 40 of the liquid from the tank through the shower nozzle.

The invention has for a still further object to generally improve and simplify the construction and operation of devices of this 45 character and increase the efficiency thereof without materially increasing the cost of the same.

With these and other objects in view as will become more apparent as the description 50 proceeds, the invention consists in certain novel features of construction, combination and arrangement of parts as will be hereinafter more fully described and claimed.

55 For a complete understanding of my invention, reference is to be had to the fol-

lowing description and accompanying drawings, in which—

Figure 1 is a transverse horizontal fragmentary view of the portable shower, Fig. 2 60 is a vertical longitudinal section.

Referring in detail to the drawings by numerals, 1 designates the body which may be constructed of metal or any other suitable material and which has the outwardly flared 65 legs 2 secured thereto to support the body in proper position with the lower end thereof a spaced distance above the floor or other support upon which the device is positioned.

Secured in the lower portion of the body 70 1 is a circumferential flange 3 which has its lower edge extended inwardly and curved downwardly, as shown at 4, to direct the water or other liquid to the tub 5 positioned beneath said body 1, it being understood 75 that the lower end 4 of the flange 3 projects over the tub 5 when the latter is in position.

The flange 3 has an upwardly and outwardly directed extension 3' which projects 80 outwardly beneath the door 6, which will be later fully and clearly described, to catch any water running down the inner face of the door and direct the same to the main portion of the flange 3 to be directed by the 85 same to the tub 5, thereby eliminating danger of the water escaping beneath the lower edge of the door 6 of the body 1.

The main portion of the body 1 is provided with a suitable door 6 mounted along 90 one longitudinal vertical edge upon the hinges 7 and a suitable knob 8 by means of which the door 6 may be swung to open position upon its hinges 7. It will be understood that the door 6 extends from the top 95 to the bottom of the main portion of the body 1, and the upper end 9 or top of the body 1 is directed inwardly and then extended upwardly, as shown at 10, with the liquid containing tank 11 secured thereto, 100 as will be readily understood by referring to the drawings. It will also be understood that it is not necessary to extend the entire body 1 upwardly above the main portion thereof as the tank 11 may be securely supported by means of the vertical strips 12 of the frame 1, with which the legs 2 are also shown as being formed integral, the depending circular flange 11' of the tank 11 being engaged over the ring 10' mounted 110 against the outer face of the upper ends of the extended vertical strips 12 and se-

cured to the same by bolts, as shown at 10, and previously mentioned. It will also be understood that the ring 9' at the upper end of the body 9 is secured against the inner 5 face of the material forming the main portion of the body 9 and along the upper edge thereof, by bolts 25 or the like and if desired the rivets shown on the drawings may be replaced by bolts so that all of the parts 10 of the device may be readily disconnected for shipping and other purposes. It will also be understood that when desired, the nozzle 15 may be readily removed from the discharge opening 14 when it is desired to 15 lift the tank 11 off of the ring 11' and place the same upon a floor or other flat surface. It will further be understood that the portions of the main part of the body between the strips 12 may be formed of metal, cork 20 or any other suitable material.

The tank 11 has a removable cover or top 13 and is provided in its bottom with an outlet or discharge opening 14 within which is secured the shower nozzle 15, having an enlarged perforated lower end 16. Positioned over the opening 14 is a flat hinge valve 17 which is secured to the supporting plate 18 fastened to the upper face of the bottom of the tank 11, as shown at 19. The valve 17 25 is normally closed or engaged over the opening 15 to prevent the liquid in the tank 11 from reaching the shower nozzle 15.

Projecting upwardly from the valve 17 is an eye 20 within which is secured one end 30 of the cord 21 which is directed upwardly at an angle and extended through the side of the tank 1 and over a guide pulley 22, then brought downwardly into the body 1 and has a handle 23 secured upon its 35 pending end, whereby the bather may readily draw downwardly upon the cord 21 to swing the valve 17 upwardly to position and permit the contents of the tank 1 to leave the same by way of the shower nozzle 15. 40 As soon as the cord 21 is released, however, the weight of the valve 17 will cause the same to again move to closed position and cut off the supply of liquid from the tank 11.

It will be understood that the tub 5 may 45 be provided with suitable handles 24 and if desired, a hook or other fastener may be secured in the body 1 for engagement by the handle 23 to retain the valve 17 in open 50 position and leave the hand of the bather free.

While I have shown and described the preferred embodiment of my invention, it will be understood that minor changes in the details of construction, combination and arrangement of parts may be made without departing from the spirit and scope of the invention as claimed.

What is claimed is:—

1. A device of the class described comprising a body, a tub beneath said body, a tank above said body, said tank being of smaller diameter than said body, said body including vertical strips, said vertical strips having their inner ends bent inwardly and extended upwardly to support said tank, 65 said vertical strips having their lower ends turned outwardly on an incline to provide legs for supporting said body, a shower nozzle depending from said tank, said tank having a discharge opening above said shower 70 nozzle, a valve normally positioned over said discharge opening, means extending into said body for opening said valve to permit the contents of said tank to reach said shower nozzle, means for guiding the 75 last mentioned means, and a flange secured in said body and having its lower edge offset inwardly from its upper edge to direct liquid from the sides of the body to said tub. 80

2. A device of the class described comprising a body, a flange secured around the lower edges of said body, said flange having its lower edges extending inwardly and curved downwardly, a ring around the upper edges of said body, a plurality of supporting strips secured to the outer surface of said body at a point near their ends, the upper terminals of said strips bent inwardly and upwardly, adapted to support a tank 90 thereon, the lower ends of said strips bent 95 outwardly forming legs to support said body and tank, said tank mounted on the upper ends of said strips and provided with a central opening on its under surface, means for controlling the flow of water 100 therefrom into said body, a tub under said body, and means for directing the liquid from the sides of the body into said tub. 105

In testimony whereof I affix my signature in presence of two witnesses.

ROBERT ALEX RUTLAND.
